United States Patent Office

Des. 182,409
Patented Apr. 1, 1958

182,409

HAT

Richard D. Frye, Erie, Mich.

Application November 29, 1957, Serial No. 48,723

Term of patent 3½ years

(Cl. D3—13)

I claim:

The ornamental design for a hat, substantially as shown.
